(57) **CLAIM**

The ornamental design for a bottle, substantially as shown and described.

DESCRIPTION

FIG. 1 is a perspective view of a bottle showing my new design;

FIG. 2 is a rear elevational view thereof, shown at a reduced scale;

FIG. 3 is a front elevational view thereof;

FIG. 4 is a left side elevational view thereof;

FIG. 5 is a top plan view thereof; and,

FIG. 7 is a bottom plan view thereof.

The broken lines shown in FIG. 7 are for illustrative purposes only and form no part of the claimed design.
